DISPENSING CARTON FOR LIQUIDS, POWDERS OR THE LIKE

Thomas W. Winstead, Baltimore, Md., assignor to Hed-win Corporation, Baltimore, Md., a corporation of Maryland

Application July 16, 1956, Serial No. 42,265

Term of patent 14 years

(Cl. D58—17)

Figure 1 is a perspective view of a dispensing carton for liquids, powders or the like showing my new design; and

I claim:

The ornamental design for a dispensing carton for liquids, powders or the like, as shown.
